UNITED STATES PATENT OFFICE.

EMIL A. RASCHKE, OF CHICAGO, ILLINOIS.

METHOD AND APPARATUS FOR MAKING COLOR-CORRECTING AND COLOR-SEPARATION NEGATIVES FOR PLATE-PRINTING TRADES.

1,373,020.

Specification of Letters Patent. Patented Mar. 29, 1921.

Application filed September 3, 1918. Serial No. 252,286.

To all whom it may concern:

Be it known that I, EMIL A. RASCHKE, a citizen of the United States, and a resident of the city of Chicago, county of Cook, and State of Illinois, have invented certain new and useful Improvements in Methods and Apparatus for Making Color-Correcting and Color-Separation Negatives for Plate-Printing Trades, of which the following is a specification.

My invention relates to improvements in method and apparatus for making color correcting and color separation negatives for plate printing trades, and has for its object the provision of an improved method and apparatus by means of which such negatives, and printing plates therefrom, may be quickly and economically made without restriction as to the size of the subject or light conditions, using either sunlight, daylight, or artificial light; by means of which rugs, oil paintings, and the like, may be photographed and reproduced as readily as pastels, with great gradation in detail formation; and by means of which such work may be done by the artists, as they are known in the lithographic arts, and by the color etchers, as they are known in the engraving arts, with great ease and expedition.

Other objects will appear hereinafter.

The invention consists in the combinations and arrangements of parts hereinafter described and claimed.

The invention will be best understood by reference to the accompanying drawings forming a part of this specification, and in which,

Figure 1, is a side view, shown partially in section, of the rear end of an ordinary camera for the purpose equipped with apparatus embodying the invention and arranged and adapted for carrying on the improved process,

Fig. 2, a front face view of a removable frame employed in the apparatus and process, and adapted to be readily inserted in or removed from the camera,

Fig. 3, a section taken on line 3-3 of Fig. 2,

Fig. 4, a section taken on line 4-4 of Fig. 2,

Fig. 5, an enlarged section taken on line 5-5 of Fig. 2,

Fig. 6, a partial horizontal section through

the rear of the camera, showing the apparatus in position,

Fig. 7, a rear elevation of the apparatus removed from the camera, and

Fig. 8, an enlarged detail section illustrating one of a plurality of adjusting screws employed in the apparatus.

The preferred form of apparatus, as illustrated in the drawings, comprises a supporting frame or carrier 9 arranged to be inserted in the rear end of the camera 10 immediately in front of the usual plate holder 11 thereof and between said plate holder and the lens of the camera. The supporting frame 9 is provided at one side with a forwardly swinging frame 12 hinged at 12' to frame 9 and provided with channeled guides 13, open at the top for the ready insertion or removal of a plain clear glass plate 14. A cord 15 is attached to frame 12 and passes over a guide pulley 16 on the forward end 65 of a post 17 on frame 9 and thence through a suitable aperture or opening in the side of the camera and by means of which the frame 12 may be swung forwardly, as indicated in full lines in Fig. 6, said cord being preferably provided on its end with a ring by means of which the same may be readily secured to a nail or the like to hold the frame 12 in its forward position when desired. A leaf spring 18, secured to frame 19 and resting loosely against frame 12 serves to swing frame 12 to its operative position over the central opening in frame 9 when desired, upon release of the cord 15, as will be readily understood. By this arrangement it will 80 be observed that unexposed sensitized plates may be inserted in the plate holder 11 and exposed to light from the subject being treated, passing through said suitable color filters, to produce the usual negatives for the 90 purpose, as will be readily understood by those skilled in this art.

Another forwardly swinging frame 19 is pivoted or hinged at 19' to the other side of supporting frame 9, and is equipped with a 100 leaf spring 20 normally holding the same in operative position. A cord 21 is secured to frame 19 and passed over guide pulley 22 and through a suitable aperture in the side of the camera 10 and by means of which 105 frame 19 may be manipulated in the same manner as frame 9, as explained above. An adjusting frame 23 is mounted within the

frame 19 for free adjustment therein, and resting at its bottom on a spring-held supporting point 24, as shown. Frame 23 carries at one side a lug 25 threaded upon an 5 adjusting shaft 26 mounted upon frame 19 and connected by beveled gears 27 with an operating shaft 28, which is carried by a lug 28' on frame 19 operating through a lug 28" on frame 19 operating through a suitable slot in frame 9, as shown. Shaft 10 28 is in turn connected by means of a detachable slot and lug connection 29 with a longitudinally movable hand shaft 30, having a knurled hand wheel 31 thereon, and whereby shaft 26 may be readily manipulated 15 to adjust the frame 23 vertically within the frame 19 and the parts freed for forward swinging of frame 19. An adjusting screw 32 is mounted in a swivel post 33 on frame 19 and is threaded in a swiveled ear 20 or lug 34 on frame 23, and whereby the frame 23 may be angularly adjusted within the frame 19, rocking or swinging upon the point 24, as will be readily understood. Frame 23 is provided in each corner with 25 an adjusting screw 35 carrying a collar 37 imprisoned between a laterally adjustable bracket 36 and the corresponding corner of the frame, and whereby other frames may be secured for forward and back adjustments. In the form of apparatus illustrated, a filler frame 38 is shown as secured 30 within the frame 23 by means of the screws 35, said filler frame being similarly equipped with these adjusting screws 35 at each corner thereof. Likewise, another filler frame 39 is shown as secured in place within the frame 38 and similarly equipped at its corners with adjusting screws 35, as shown. A negative holding frame 40 is secured within 35 the filler frame 39 by means of its adjusting screws 35, said negative frame being grooved on its sides, just as is frame 12, and adapted to receive various negatives, when desired. By omitting or using one or more of the 40 filler and negative frames, negatives of various sizes may be provided for. An arrangement providing for larger negatives has been illustrated in Fig. 7, wherein a negative frame 40' is shown as mounted in frame 45 23 to receive larger negatives 41'. -

In carrying on the improved process, the frame 12 is first adjusted to position on frame 9 directly in front of the plate holder 11 and parallel thereto, and preliminary 50 negatives obtained by exposing sensitized plates to the subject through different color filters and the clear glass 14 in the usual manner, to obtain negatives for the production of the different plates for producing 55 the different colors of the subject. Thus, negatives will be made by making exposures through violet, green, red, or any suitable color filter in frame 12, depending upon the colors in the subject which it is desired to reproduce and as will be readily understood

by those skilled in the art. These various preliminary negatives are developed, fixed and washed in the usual manner. Then, one of these negatives suitable to the required or desired separation, say for instance, for the yellow printing plate, or the red printing plate, or the blue printing plate, or the black printing plate is selected, the operator depending upon his skill and experience in this art in making a selection of the negative 75 which will give the best results for the color plate desired. Each of the negatives thus selected for the different plates for producing the different colors is in turn placed in the frame 19, which, of course, is previously 80 adjusted to parallel position before the plate holder 11, the frame 12 being swung forwardly for the purpose, as indicated in Fig. 6. After each negative has been thus placed in operative position in the camera, its holding frame is nicely adjusted by means of the various adjustments provided until said negative is brought into proper register with the image of the subject in the camera, as will be readily understood by those skilled 85 in this art. To accomplish nice registration, it will be observed that vertical, angular, and forward and back adjustments are provided, so that the negatives may be thus 90 delicately adjusted to proper registration 95 with the image of the subject.

After each of the preliminary negatives has thus been placed in registration with the image in the camera, an unexposed sensitive plate is arranged in the plate holder 11 and 100 exposed through a suitable color filter, with the negative as a screen, and permitting only those portions of light which indicate clear glass to act on the plate in the plate holder for a given time, such time being determined 105 by the skill and judgment of the operator, depending upon the light conditions, the subject in hand, the character and qualities of the lens of the camera, as is usual in this art. After a suitable exposure, depending 110 upon the judgment of the operator, the lens of the camera is "capped" or closed, and the negative withdrawn from its registering position by means of the cord 21 extending to the outside of the camera, such withdrawal 115 being thus permitted without disturbing the relations of the image of the subject to the plate in the plate holder. The exposure is then completed through the proper color filter in the usual manner, and for a time depending upon the judgment of the operator, as above outlined. The plate thus produced is removed, developed, fixed and washed in the usual manner, and is then ready for use in the usual manner for the production of 120 a printing plate to print the corresponding color in the subject under treatment. Likewise, other negatives are those produced for the other colors in the subject, and from them corresponding plates are produced in 125 130

the usual manner for the corresponding colors of the subject, all as will be readily understood by those skilled in the art, the present invention relating only to the production of the proper negatives or plates for the purpose, it being well known and understood in this art how to produce the actual printing plates from these negatives.

In this manner and by use of the apparatus disclosed, plates for reproducing the various colors in a subject matter will be readily and economically provided, irrespective of the size of the subject or the light conditions, and with great gradation in detail formation.

While I have illustrated and described the preferred method of procedure and apparatus for carrying on the same, these are capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:—

1. The method of making negatives from which printing plates may be produced which consists in first making a negative of the subject; then exposing a plate to light from said subject passing through said negative; then exposing said plate to direct light from said subject; and then developing said plate, substantially as described.

2. The method of making negatives from which printing plates may be produced which consists in first making a negative of the subject by means of color filtered light therefrom; then exposing a plate to color filtered light from said subject passing through said negative; then exposing said plate to direct light from said subject; and then developing said plate, substantially as described.

3. The method of making negatives from which printing plates may be produced which consists in first making a series of negatives of the subject by means of color filtered light therefrom; then exposing plates to light from said subject passing through said negatives; then exposing said plates to direct light from said subject; and then developing said plates, substantially as described.

4. The method of making negatives from which printing plates may be produced which consists in first making a plurality of negatives of the subject by means of color filtered light therefrom; then exposing a plurality of plates to color filtered light from said subject passing through said negatives for different times; then exposing said plates to direct color filtered light from said

subject; and then developing said plates, substantially as described.

5. The method of making negatives from which printing plates may be produced which consists in first making a negative of the subject by means of color filtered light therefrom; then exposing a plate through a suitable color filter to light from said subject passing through said negative; then exposing said plate to color filtered light from said subject with said negative removed; and then developing said plate, substantially as described.

6. The method of making negatives from which printing plates may be produced which consists in first making a plurality of negatives of the subject by exposing plates to color filtered light from said subject; then exposing plates to color filtered light from said subject passing through said negatives for different lengths of time; then exposing said plates to color filtered light from said subject with the corresponding negative removed; and then developing said plates, substantially as described.

7. Apparatus for making negatives from which printing plates may be produced comprising a camera having a plate holder; a negative holder arranged in front of said plate holder; and means for temporarily removing said negative holder from in front of said plate holder, substantially as described.

8. Apparatus for making negatives from which printing plates may be produced comprising a camera having a plate holder; an adjustable negative holder arranged in front of said plate holder; and means for temporarily removing said negative holder from in front of the plate holder, substantially as described.

9. Apparatus for making negatives from which printing plates may be produced comprising a camera having a plate holder; a clear glass member arranged to be positioned in front of said plate holder; a negative holding member arranged to be positioned in front of said plate holder; and means for temporarily removing and replacing said clear glass member and said negative holder, substantially as described.

10. Apparatus for making negatives from which printing plates may be produced comprising a camera having a plate holder; a clear glass member arranged to be positioned in front of said plate holder; an adjustable negative holding member arranged to be positioned in front of said plate holder; and means for temporarily removing and replacing said clear glass member and said negative holder, substantially as described.

11. Apparatus for making negatives from which printing plates may be produced comprising a camera having a plate holder; a

negative holding member arranged in front of said plate holder; means adapting said negative holder to the reception of negatives of various sizes; and means for temporarily removing said negative holder; substantially as described.

12. Apparatus for making negatives from which printing plates may be produced comprising a camera having a plate holder; an 10 adjustable negative holding member arranged in front of said plate holder; means adapting said negative holder to the reception of negatives of various sizes; and means for temporarily removing said negative 15 holder, substantially as described.

13. Apparatus for making negatives from which printing plates may be produced comprising a camera having a plate holder; a color filter member arranged to be positioned in front of said plate holder; a negative holding member arranged to be positioned in front of said plate holder; means adapting said negative holder to the reception of negatives of various sizes; and means 25 temporarily removing and replacing said filter member and said negative holder, substantially as described.

14. Apparatus for making negatives from which printing plates may be produced comprising a camera having a plate holder; a color filter member arranged to be positioned in front of said plate holder; an adjustable negative holding member arranged to be positioned in front of said plate holder; means adapting said negative holder to the 35 reception of negatives of various sizes; and

means temporarily removing and replacing said filter member and said negative holder, substantially as described.

15. Apparatus for making negatives from 40 which printing plates may be produced comprising a camera having a plate holder; a frame insertible in said camera in front of said plate holder; two forwardly swinging frames on said insertible frame, said swinging frames being provided with glass holding means; and means, on the outside of said camera, for manipulating said swinging frames, substantially as described.

16. Apparatus for making negatives from 45 which printing plates may be produced comprising a camera having a plate holder; a frame insertible in said camera in front of said plate holder; a swinging frame on said insertible frame provided with means for holding a clear glass plate; a second swing frame on said insertible frame; a negative holding frame mounted on said second swinging frame; means for adjusting said negative frame vertically, forward, and 50 back and angularly in said second swinging frame; and means, on the outside of said camera, for manipulating said swinging frames, substantially as described.

In testimony whereof I have signed my 55 name to this specification in the presence of two subscribing witnesses.

EMIL A. RASCHKE.
